UNITED STATES PATENT OFFICE.

FRANK E. BECKER, OF JAMAICA, NEW YORK, ASSIGNOR TO UNDERWOOD TYPEWRITER COMPANY, OF NEW YORK, N. Y., A CORPORATION OF DELAWARE.

TYPE-WRITING MACHINE.

1,159,886.

Specification of Letters Patent.

Patented Nov. 9, 1915.

Application filed February 8, 1913. Serial No. 746,999.

To all whom it may concern:

Be it known that I, FRANK E. BECKER, a citizen of the United States, residing in Jamaica, borough of Queens, in the county of Queens and State of New York, have invented certain new and useful Improvements in Type-Writing Machines, of which the following is a specification.

My invention relates to typewriting machines, and particularly to means for connecting and disconnecting the platen and line-space wheel, for fractional line-spacing, etc.

The invention involves a principle of construction disclosed in the patent to Arthur W. Smith, No. 860,834, in which the line-space wheel and the platen are relatively rotatable, a locking dog being carried by one of said parts, and a toothed rack or ring carried by the other part, the locking dog being adapted for movement into locking engagement with the said toothed ring, the line-space wheel and platen being thus locked together regardless of their relative positions.

According to the present invention the locking dogs are arranged to positively prevent any relative movement whatever of the line-space wheel and platen when the parts are in locking position.

An important feature of the invention is the provision of a number of locking dogs arranged to be operated independently of one another to locking position, and so arranged that oppositely acting dogs are relied upon to hold the parts against relative movement in opposite directions. In other words each dog is required to lock the toothed wheel with which it engages against movement in only one direction. By such arrangement the liability to looseness of parts or lost motion, due to wear or inaccuracy in manufacture or unevenness in the spacing of the gear-teeth, is entirely eliminated. A strong and reliable structure is also thereby obtained. The dogs are moved directly into locking position simply by rotation about their pivots and are positively locked in such position by individual wedge cams; making a simple and effective structure. The dogs are independently operated and each moves fully up to locking engagement with the toothed wheel regardless of the position of the other dogs or the relative position of the platen and line-space wheel.

The line-space wheel is loosely mounted on the platen axle, but is normally held against rotation relative to the platen by locking dogs carried by the line-space wheel, and engaging teeth of a toothed ring having a fixed connection with the platen axle. The said ring is preferably secured within a drum fixed to the axle. The locking dogs are arranged in pairs and pivotally mounted on supports fixed to the line-space wheel. These locking dogs lie in the plane of the toothed ring, and are moved to locking position by spring actuated wedge shaped cams guided on pins secured to the line-space wheel and parallel to the platen axle. Each cam is movable independently of the others and follows up a locking dog, moving it into engagement with the toothed ring. Thus each dog is movable independently into a position to positively lock the said ring against rotation in one direction. The locking dogs are so spaced that when one dog of the pair locks the said ring in one direction, the other dog engages a tooth at a point to prevent rotation in the reverse direction. By the provision of a plurality of locking dogs, the danger of any lost motion or looseness of the parts when locked due to wear is practically eliminated, and a strong and reliable construction is also obtained. The locking cams are retracted by means of a thumb piece carrying a disk in position to engage the cams and move them to releasing position.

Other features and advantages will hereinafter appear.

In the accompanying drawing, Figure 1 is a perspective view of mechanism embodying the principles of my invention. Fig. 2 is a sectional end elevation view showing the parts in locking position. Fig. 3 is a similar view showing the locking dogs released. Fig. 4 is a sectional view as indicated by the line 4-4 of Fig. 2. Fig. 5 is a perspective view of the line-space wheel, the locking dogs and a dog-operating wedge, the parts being disassembled. Fig. 6 is a perspective view of the internal gear. Fig. 7 is a perspective view of one of the dog-operating wedges.

The platen 1 is fixed to an axle 2 journaled in a platen frame 3. A line-space lever 4 is adapted to operate a slide 5 to which is pivoted a dog 6 having a tooth 7 to engage the teeth of a line-space wheel 8 loosely

mounted on the axle 2. The line-space wheel is normally connected, through mechanism presently to be described, to rotate the platen. The operation of the lever 4 rotates 5 the wheel and platen in the usual manner, the slide 5 and lever 4 being returned by a spring 9 secured at its ends to the slide and platen frame. A detent 10 engaging the line-space wheel holds the latter against 10 accidental rotation.

Rigidly secured to the line-space wheel 8 are four guide pins 11 extending from one side of the wheel parallel with the platen axle and preferably equally spaced and equi- 15 distant from the axle. Also rigidly secured to the line-space wheel, by any suitable means as for example, screws 12, are two supporting members 13 on the outer ends of which are mounted two pairs of locking 20 dogs *a*, *b*, and *c*, *d*. Each pair of dogs is mounted on a pivot 14 threaded into a corresponding opening 15 in the end of its support 13. Each locking dog is formed at its outer end with a tooth 16 adapted to 25 engage the rack teeth 17 of an internally toothed ring or clutch member 18 connected to a drum or casing 19 by screws 20. The ring 18 and locking dogs form respectively the members of a clutch to connect the 30 platen and line-space wheel 8. The drum 19 is provided at its outer end with a web 21 formed with a sleeve or hub 22, which fits on the platen axle 2. A set screw 23 secures the drum rigidly to the axle.

35 The locking dogs are moved to locking position by means of wedge-shaped cams 24 formed integral with or rigidly secured to cam blocks 25 which slide on the guide pins 11. Each block 25 is formed with grooves 40 or semi-cylindrical recesses 26 in its side faces, which form bearing surfaces to receive the pins 11. The inner corner of the block 25 is also removed to form a curved surface 27, which bears on the axle 2.

45 Each wedge 24 presents an inclined or cam face 28, which is also preferably somewhat curved or convexed, as indicated in Figs. 5 and 7. The locking dogs are formed with bearing faces 29, which bear on the cam 50 surfaces 28. The inner lateral face of each wedge 24 may bear against a lateral face of one of the supports 13, as shown in Figs. 2 and 3. Each of the locking wedges is normally held outward in a locking position by 55 means of a coil-spring 30 seated in a recess in the block 25 and reacting against the line-space wheel 8.

Secured to the outer end of the platen axle, by means of a set screw 32, is the usual 60 finger-wheel 31 for rotating the platen. The locking dogs are adapted to be released by means of a thumb-piece or button 33 secured to the outer ends of parallel rods 34, which extend through the finger-wheel 31, and at 65 their inner ends carry a disk 35 in front of

the cam blocks 25. Normally the locking dogs and their actuating wedges 24 are held in locking position by the springs 30, so that relative rotation of the line-space wheel and the platen is prevented, and the platen is rotated for ordinary line-spacing through the 70 operation of the line-space lever 4.

To permit rotation of the platen through the fraction of a line-space, pressure is applied to the thumb-piece 33, and the wedge 75 blocks 25 are thereby forced inward toward the line-space wheel, which releases the locking dogs. The latter are then moved inward about their pivots by springs 36, which may be secured at their inner ends to the 80 line-space wheel and extend through openings 37 in the supports 13, the other ends of springs engaging in openings 38 in the locking dogs. These springs tend to swing locking dogs inward toward released position. 85 Inward pressure of the thumb-piece 33 therefore releases the locking dogs from the locking ring 18 and permits rotation of the platen, while the line-space wheel is held stationary by the detent 10. When the 90 thumb-piece 33 is again released, the springs 30 force the cams outwardly and lock the dogs to the ring 18.

By reference to Fig. 2, it will be seen that the relation of the teeth 16 of the locking 95 dogs to the teeth 17 varies for any given relative position of line-space wheel and platen. In other words, the distance between the teeth of each pair of locking dogs is not an even multiple of the distance between the points of two adjacent teeth 17. Thus, as shown in this figure, the tooth on the dog *c* is seated between two of the teeth 17, while the tooth on the dog *d* engages the point of a tooth 17. The 100 result of this arrangement is that the two dogs will lock the platen against rotation in either direction regardless of the relative position of the platen and line-space wheel, which would not be the case if the 105 locking dogs were so spaced as to engage the same relative portions of the teeth 17. It will also be observed that for a given relative position of the line-space wheel and platen, the position of the pair of dogs *a*, *b*, 110 with respect to the teeth 17 is different from that of the dogs *c*, *d*. Thus in Fig. 2, the dog *a* locks the ring 18 against rotation in a counter-clockwise direction, and the dog *b* locks the ring against rotation in the reverse 115 direction; the dog *c* has its teeth seated between two of the teeth 17, so as to lock the ring against rotation in either direction; and the dog *d* is at the point where it cannot prevent rotation of the ring in either direction. 120

Considering either pair of dogs alone, as for example the dogs *c* and *d*, and assuming the dogs to be retracted, it will be apparent that if the ring 18 is rotated in either direc- 125 130

tion through an angle less than half the distance between two adjacent teeth 17, and the dogs again released, they will both be in locking position and prevent rotation in either direction. If the ring has been rotated through half the angular distance between adjacent teeth, the relation of the two dogs to the teeth will be reversed, that is, the tooth on the dog *c* will engage the point of a tooth 17, while the tooth on the dog *d* will be seated between two of the teeth 17. It will thus be apparent that either pair of dogs alone would suffice to positively hold the parts, regardless of the relative position of the platen and line-space wheel. The use of two pairs of locking dogs, however, provides a somewhat more reliable and symmetrical construction.

It will be noted that the cam blocks 25 will be moved outward a greater or less distance, depending on the relation of the locking dog operated thereby to the teeth 17. Thus, for example the tooth on the dog *c* Fig. 2, being seated between two of the teeth 17, is moved farther than the tooth on the dog *d*, requiring that the actuating block 25 for the dog *c* be moved outward a greater distance than that for the dog *d*. The thumb-piece 33, when pressed inward, holds the cams inward an equal distance and thereby permits a uniform retraction of the locking dogs.

Variations may be resorted to within the scope of the invention, and portions of the improvements may be used without others.

Having thus described my invention, I claim:

1. In a typewriting machine, the combination with a platen axle and a platen secured thereto, of a line-space wheel mounted to rotate on the platen axle, a drum fixed to the axle, an internally toothed ring secured to the drum, pivoted locking dogs carried by the line-space wheel and independently movable into locking engagement with said ring, cams to independently operate said dog, and a device to operate said cams.

2. In a typewriting machine, the combination with a platen, its axle and a line-space wheel, of a drum secured to the platen axle, an internally toothed ring secured within said drum, locking dogs carried by the line-space wheel and each rotatable about a pivot parallel with the platen axle, cams movable longitudinally of said axle to independently operate said locking dogs, and a thumb-piece to operate said cams.

3. In a typewriting machine, the combination with a platen axle and a platen, of a line-space wheel rotatable on said axle, a casing secured to the axle, an internally toothed ring secured within the casing, locking dogs, means connecting said dogs to the line-space wheel, wedges to actuate said locking dogs, guide pins carried by the line-space

wheel for supporting and guiding said wedges, springs to actuate said wedges in a direction to operate the dogs to locking position, springs to retract the dogs to released position, and a manual device operable to return the said wedges and permit the release of the locking dogs.

4. In a typewriting machine, the combination with a platen and a line-space wheel, of a clutch to connect said parts comprising a rack and locking dogs arranged in pairs, the dogs of each pair pivoted to rotate about the same axis, and swinging outwardly in the plane of the rack into engagement with the rack and positioned to form a locking connection with different relative portions of the rack teeth, and thereby lock the line-space wheel and platen in any relative position.

5. In a typewriting machine, the combination with a platen and a line-space wheel, of a clutch to connect said parts comprising a member having pointed teeth and independently movable pivoted dogs having pointed teeth co-operating with the teeth on said member; said dogs arranged in pairs, the dogs of each pair pivoted to rotate about the same axis, and individual operating means to swing each dog outwardly to engage with said member, the relative position of said dogs being such that when the point of one dog tooth engages the point of a tooth on said member, the tooth on the other dog is fully seated in a notch between two adjacent teeth on said member.

6. In a typewriting machine, the combination with a platen and a line-space wheel, of a clutch to releasably connect said platen and wheel comprising a member having an annular series of teeth and a pair of clutch dogs in the plane of said member, said dogs pivoted for rotation about the same axis, and means to independently actuate said dogs.

7. In a typewriting machine, the combination with a platen and a line-space wheel, of a clutch to releasably connect said platen and wheel comprising a member formed with an annular series of clutch teeth, and a pair of clutch dogs pivoted for rotation about a common axis into and out of engagement with said teeth, the contacting surfaces of said teeth being inclined to both their direction of movement and also to the direction of movement of the locking dogs, said dogs being of such length relative to the spacing of the teeth as to lock the platen and line-space wheel together in any position of adjustment.

8. In a typewriting machine, the combination with a platen and a line-space wheel adapted for relative rotation, of a clutch to connect said parts comprising a ring of rack teeth and independently movable pivoted locking dogs arranged in pairs with the dogs

- of each pair extending in opposite directions from their pivots, the pivots and rack-engaging portions being arranged substantially in the circumference of a circle within 5 said ring, and means to swing said rack-engaging portions outwardly into engagement with the rack teeth, to lock the platen and line-space wheel against relative rotation from any position of adjustment.
10. In a typewriting machine, the combination with a platen and a relatively rotatable line-space wheel, of a clutch to connect said parts comprising a ring of teeth and pivoted locking dogs each having a tooth to engage the teeth of said ring, spring-operated cams encircled by the dogs and operating to actuate the latter in one direction, and manual means to operate the dogs in the opposite direction, said dogs swinging 15 outwardly into engagement with said teeth to lock the platen in any position to which it may be rotated relatively to the line-space wheel, said cams engaging behind the teeth of the dogs and forming a solid backing by 20 which the teeth of the dogs are rigidly held against the teeth of the ring and positively prevented from yielding or moving relatively to the ring.
11. In a typewriting machine, the combination with a line-space wheel and a platen; of a clutch to connect said parts comprising a rack and a ring of pivoted dogs arranged in pairs, the dogs of each pair extending in opposite directions from their pivots and 30 independently movable about their pivots and swinging outwardly into engagement with the rack, and means surrounded by said dogs to actuate them, said rack and dogs having coöoperating pointed teeth to lock the 35 platen and line-space wheel in any relative position of adjustment.
12. In a typewriting machine, the combination with a platen and a line-space wheel mounted for relative rotation, of a clutch to 40 connect said parts comprising a toothed member and a ring of pivoted dogs adapted for independent pivotal movement, and individual means to swing each dog outwardly 45 into engagement with the said toothed member; the locking dogs being arranged in pairs, the dogs of each pair extending in opposite directions from their pivots and so positioned relatively to each other and to the toothed member that when one dog of 50 a pair locks said parts against relative rotation in one direction, the other locks the parts against relative rotation in the opposite direction.
13. In a typewriting machine, the combination with a rotary platen and a relatively 55 rotatable line-space wheel, of a clutch between said parts comprising a toothed locking ring and pivoted toothed dogs arranged with their teeth and pivots in a ring within said locking ring, said dogs arranged in pairs with the dogs of a pair extending in opposite directions from their pivots and independently movable to swing outwardly for locking engagement with said ring, the relative position of the dogs of a pair being 60 such that when one dog is in position to lock the ring against rotation in one direction only, the other dog is in position to lock the ring against rotation in the opposite direction.
14. In a typewriting machine, the combination with a line-space wheel and a relatively rotatable platen having an axle, of a clutch to connect said wheel and platen, the clutch comprising a ring of teeth, pivoted 65 locking dogs within said ring, and having locking portions to swing into engagement with the said teeth, said locking portions arranged at diametrically opposite sides of the platen axle, and means for operating the 70 dogs, said means, when the dogs are in locking position, being interposed between the platen axle and said engaging portions of the dogs, whereby the locking strain created 75 at one side of the axle and transmitted from one locking dog through said means to the axle is counter-acted by the locking strain transmitted from the diametrically opposite dog through said means to the axle.
15. In a typewriting machine, the combination with a platen and a line-space wheel, of a clutch between said parts comprising a toothed ring and a plurality of pivoted locking dogs, each having a locking portion to engage said ring, said locking portions and the pivots of said dogs arranged in a ring, 80 said dogs independently rotatable in the plane of said toothed ring and swinging outwardly into engagement with its teeth, the contacting surfaces of the dogs and ring teeth each inclined to its direction of movement and the faces of said teeth each being of an extent to be engaged at a plurality of points by each locking dog, the point of contact infinitesimally variable by a rotation of the platen relatively to the line-space wheel, 85 and means surrounded by said ring of dogs to actuate said dogs.
16. In a typewriting machine, the combination with a platen and line-space wheel, of 90

a clutch to releasably connect the platen and wheel, said clutch comprising an annular series of rack teeth and pivoted locking dogs arranged in pairs, each pair having a common pivot, the dogs of each pair extending in opposite directions from their pivot and provided with teeth arranged to engage said first-mentioned teeth and lock the platen to the line-space wheel in any rotative position 5 of the platen relative to said wheel, and locking cams interposed between the platen axle and the teeth of the locking dogs for

moving the latter into locking position, said cams acting on said locking dogs at points on diametrically opposite sides of the platen axle, whereby the re-acting pressure of each locking dog is transmitted to the platen axle and counter-balanced by the re-acting pressure of the opposite locking dog. 15
